UNITED STATES PATENT OFFICE.

CARL WILHELM SÖDERBERG, OF CHRISTIANIA, NORWAY, ASSIGNOR TO DET NORSKE AKTIESELSKAB FOR ELEKTROKEMISK INDUSTRI, OF CHRISTIANIA, NORWAY, A BUSINESS ENTITY.

METHOD OF SUSPENDING ELECTRODES.

Application filed January 27, 1920. Serial No. 354,369.

To all whom it may concern:

Be it known that I, CARL WILHELM SÖDERBERG, a subject of Norway, and a resident of Christiania, Kingdom of Norway, 5 have invented certain new and useful Improvements in the Methods of Suspending Electrodes, of which the following is a specification.

This invention relates to electrodes being 10 baked in the electric furnace in which they are used and the object of the invention is a method whereby such electrodes may be suspended from their lower part which is baked and consequently hard.

15 In the baking of electrodes in the electric furnace in which they are used the electrodes have either been suspended from a metallic core around which the raw electrode mass has been tamped such as set forth in my 20 U. S. patent application Serial No. 205,416 filed December 4, 1917, or in a metallic mantle enveloping the electrode mass, Serial No. 322,840, filed September 8, 1919.

According to my present invention I 25 suspend the electrode from its lower baked part, thus obtaining great advantage in that the weight of the electrode instead of causing a strain in the electrode mass serves to compress it and secure a compactness of the 30 electrode at the point where baking takes place.

I can attach the holder to the baked electrode mass in various ways. It may be advantageous to attach the holder externally 35 around the electrode, but it may also in certain cases be attached internally. In certain types of furnace the latter arrangement may be preferable as the holder may then be placed very low down, even lower than the 40 roof of the furnace.

On account of the comparatively high temperature in the lower part of the electrode it may be necessary to arrange cooling of the holder either in the form of water 45 cooling or by other known means. This is especially necessary when internal holders are used.

By my method of suspending the electrode a metallic core or casing may if desired be 50 completely avoided, and no metal will then enter the furnace together with the electrode. In many cases, however, it is advantageous with my present method to employ a metallic mantle and in case of internal suspension

also a tubular metallic lining to which the 55 holder may be attached.

As the lower part of the electrode is gradually consumed the holder is detached and moved upwards, care being taken not to move the holder above the baked and 60 hard part of the electrode. The holder is then again attached and the electrode may be lowered as commonly practiced with ordinary electrodes. New electrode mass may be supplied to the top of the electrode in 65 channelled or solid electrode form through a mold or otherwise as may be desired in each special case, and the electrode thus be made continuously in the furnace in which it is employed; or in the alternative electrodes of a definite length may be employed which when consumed may be replaced by new electrodes. In the latter case the individual electrodes must be prebaked at least 70 in the part to which the holder is attached. 75

In the drawings forming part of this application I have illustrated my invention, Figure 1 showing an electrode suspended by an external holder and Figure 2 by an internal holder. 80

In Figure 1 *a* designates an open electric furnace, *b* the baked part of the electrode, *c* the unbaked or only slightly baked part of the electrode, and *d* a mantle into which the raw electrode mass is tamped. This mantle 85 as illustrated in the drawings has the character of a mold and does not follow the electrode into the furnace but is displaced upwards together with the holder *f*. The supplying of the electrode mass and the tamping 90 of the same into the mantle may be readily effected from the platform *e*. The holder *f* is illustrated as attached to the baked part of the electrode below the mantle *d* and suspended by cables *g*, the holders shown being of the well known clamped ring type. 95

In carrying out my invention with the form illustrated in Figure 1, I proceed as follows:—

An electrode formed from raw electrode 100 mass and baked at its lower end by a preliminary heating is placed in the mantle *d* and suspended over the electric furnace *a* by means of the cables *g*. An electric current is supplied to the holder either 105 through the cables *g* or through a special connection. The current will pass through the holder *f* and the baked part of the electrode

into the electric furnace. The electrode mass will gradually become baked also in its upper part by means of heat from the electric furnace. The electrode holder *f* may therefore gradually be moved upwards, the electrode still being suspended only in its baked part. The mantle or mould *d* in this particular illustration is moved upwards together with the holder *f*, and it will be understood that no metal will be brought into the furnace by the electrode. As the electrode is consumed and lowered new electrode mass is tamped into the mantle or mould *d*, the electrode thus being made continuously. 15 Figure 2 illustrates my invention in connection with an internal holder, a closed electric furnace *h* being shown. As in the case of Figure 1 the lower part *i* of the electrode is baked and the upper part *k* is unbaked or only slightly baked and a mold or mantle *l* is illustrated which does not enter the furnace. The holder *m* is water cooled and extends into a longitudinal channel formed through the center of the electrode. The holder consists of a tube split at its lower end into several sections which are pressed into holding engagement with the baked part of the electrode *i* by means of a wedge *n* when the wedge is pulled upwards by means of the rod *o*. The holder *m* is attached to a clamp or similar device *q* hanging in the chains or cables *p*. The electric current is supplied through the leads *r*. 30 In carrying out my invention with the form illustrated in Figure 2, I proceed as follows:—

An electrode formed from raw electrode mass and baked at its lower end by a preliminary heating is placed in the closed electric furnace *h*. The electrode is formed with a channel through its center and through this channel I introduce the holder *m*. When the lower end of the tube has extended down to the baked part of the electrode *i*, I pull the rod *o* upwards thereby raising the wedge and pressing the lower end of the holder tight to the baked part of the electrode. The electrode will now 45 hang from the lower part of the tube. As the electrode becomes baked by means of heat from the electric furnace and is consumed therein the wedge may be pushed down thus loosening the grip of the holder, 50 and the latter may be moved upwards to a suitable distance from the melting crater of the furnace and again tightened. New electrode mass is from time to time tamped into the mould or mantle *l* thus compensating 55 for the consumption at the working end of the electrode.

As will be understood from above example this method of suspending electrodes offers special advantages for closed types of 60 electric furnaces, and the channel through

the electrode may then if desired be used for introducing or removing gas and also for charging the furnace.

The foregoing detailed description has been given for clearness of understanding only and no undue limitation should be deduced therefrom but the appended claims should be construed as broadly as permissible in view of the prior art.

What I claim as new and desire to secure 75 by Letters Patent of the United States is:

1. Method of suspending electrodes being baked in the electric furnace in which they are used which consists in attaching a holder to the lower baked part of the electrode 80 and suspending the electrode therefrom.

2. Method of suspending electrodes being baked in the electric furnace in which they are used which consists in attaching a holder to the lower baked part of the electrode 85 and suspending the electrode therefrom and from time to time moving the holder upwards as the electrode is consumed.

3. Method of suspending electrodes being baked in the electric furnace in which they 90 are used which consists in attaching a holder internally in a longitudinal channel through the electrode and suspending the electrode therefrom.

4. Method of suspending electrodes being baked in the electric furnace in which they are used which consists in introducing a tube into a longitudinal channel through the electrode and attaching said tube to the lower part of the electrode and suspending 100 the electrode from said tube.

5. Method of suspending electrodes being baked in the electric furnace in which they are used which consists in introducing a tube into a longitudinal channel through the 105 electrode, said tube being split up at its lower end and a rod passing through the tube provided with a wedge mounted on its lower end, attaching the lower end of the tube to the baked part of the electrode by 110 pulling said wedge upwards and suspending the electrode from said tube.

6. Method of suspending electrodes being baked in the electric furnace in which they are used which consists in introducing a 115 metal tube into a longitudinal channel through the electrode, said metal tube being split up at its lower end and a rod passing through the metal tube provided with a wedge mounted on its lower end, attaching the lower end of the metal tube to the baked part of the electrode by 120 pulling said wedge upwards and suspending the electrode from said metal tube.

7. Method of suspending electrodes being 125 baked in the electric furnace in which they are used which consists in introducing a metal tube into a longitudinal channel through the electrode, said metal tube being split up at its lower end and a rod passing 130

- through the metal tube provided with a wedge mounted on its lower end, attaching the lower end of the metal tube to the baked part of the electrode by pulling said wedge upwards and suspending the electrode from said metal tube, said metal tube being provided with water cooling.
8. Method of suspending electrodes being baked in the electric furnace in which they are used which consists in introducing a metal tube into a longitudinal channel through the electrode, said metal tube being split up at its lower end and a rod passing through the metal tube provided with a wedge mounted on its lower end, attaching the lower end of the metal tube to the baked part of the electrode by pulling said wedge upwards and suspending the electrode from said metal tube, said tube being provided with water cooling, and from time to time moving the tube upwards as the lower end of the electrode is consumed.
9. The process of producing carbon electrodes in the furnace in which they are being employed, which comprises baking the lower part of the electrode by the heat from said furnace, suspending the electrode by a clamping action exerted at the level of a baked portion thereof, and supplying raw electrode material to the top of the electrode, whereby tensile strain in the electrode above the baked portion is avoided.
10. The process of producing carbon electrodes continually in the furnace in which they are being employed, which comprises baking the lower part of the electrode by the heat from said furnace, suspending the electrode by a clamping action exerted at the level of a baked portion thereof by an electrode holder, and supplying raw electrode material to the top of the electrode and moving the electrode holder upwardly in respect to the electrode as the electrode is consumed.
11. The process of producing a carbon electrode provided with a longitudinal channel in the furnace in which it is being employed, which comprises baking the lower part of the electrode by the heat from the said furnace, suspending the electrode from the baked portion thereof and supplying raw electrode material to the top of the electrode in channelled electrode form, whereby tensile strain in the electrode above the baked portion is avoided.
12. The process of producing a carbon electrode provided with a longitudinal channel in the furnace in which it is being employed, which comprises baking the lower part of the electrode by the heat from the said furnace, suspending the electrode from the baked portion thereof by an inside electrode-holder, and supplying raw electrode material to the top of the electrode in channelled electrode form.
13. The process of producing a carbon electrode provided with a longitudinal channel continually in the furnace in which it is being employed, which comprises baking the lower part of the electrode by the heat from the said furnace, suspending the electrode from the baked portion thereof by an electrode-holder, and supplying raw electrode material to the top of the electrode in channelled electrode form and moving the electrode-holder upwardly in respect to the electrode as the electrode is consumed.
14. The process of producing a carbon electrode provided with a longitudinal channel continually in the furnace in which it is being employed, which comprises baking the lower part of the electrode by the heat from the said furnace, suspending the electrode from the baked portion thereof by an inside electrode-holder, and supplying raw electrode material to the top of the electrode in channelled electrode form and moving the electrode-holder upwardly in respect to the electrode as the electrode is consumed.
15. The process of producing carbon electrodes continually in the furnace in which they are being employed, which comprises baking the lower part of the electrode by the heat from the said furnace, suspending the electrode from the baked portion thereof by an electrode-holder, and supplying raw electrode material to the top of the electrode through a mold and moving the electrode-holder upwardly in respect to the electrode as the electrode is consumed.
16. The process of producing a carbon electrode provided with a longitudinal channel continually in the furnace in which it is being employed, which comprises baking the lower part of the electrode by the heat from the said furnace, suspending the electrode from the baked portion thereof by an electrode-holder, and supplying raw electrode material to the top of the electrode through a mold in channelled electrode form and moving the electrode-holder upwardly in respect to the electrode as the electrode is consumed.
17. The process of producing a carbon electrode provided with a longitudinal channel continually in the furnace in which it is being employed, which comprises baking the lower part of the electrode by the heat from the said furnace, suspending the electrode from the baked portion thereof by an inside electrode-holder, and supplying raw electrode material to the top of the electrode through a mold in channelled electrode form and moving the electrode-holder upwardly in respect to the electrode as the electrode is consumed.
18. As a new and useful article of manufacture, a channelled electrode baked in the furnace in which it is used and adapted for the introduction into or removal from the furnace of gas, said electrode comprising

- when in use a baked portion and a partially baked portion.
19. As a new and useful article of manufacture, an electrode provided with a feeding channel baked in the furnace in which it is used and comprising when in use a baked portion and a partially baked portion.
20. As a new and useful article of manufacture, an electrode for use in an electric furnace provided with a channel adapted for charging the furnace and comprising a body portion structurally differing at its two ends, the conductivity of the body portion being permanently greater at the working end thereof.
21. As a new and useful article of manufacture, an electrode baked in the furnace in which it is used and comprising when in use a baked portion and a partially baked portion, the compactness of the electrode increasing toward the working end thereof.
22. The combination of an electrode provided with an internal longitudinal channel and means within the channel for supporting the electrode.
23. The combination of a hollow electrode and holder therefor projecting down into the hollow of the electrode and movable longitudinally in respect to the electrode.
24. An inside holder for a hollow electrode comprising cooperating members movable in respect to each other to create a clamping action in the holder to sustain the electrode.
25. An inside holder for a hollow electrode comprising cooperating members movable in respect to each other to expand the holder to cause it to clamp the electrode.
26. In combination with a hollow electrode having a clamping surface on its interior, a holder therefor adapted to be inserted within the hollow of the electrode, and comprising cooperating members movable in respect to each other to create a clamping action between the holder and the clamping surface on the interior of the electrode.
27. In an inside holder for a hollow electrode the combination of cooperating members, movable in respect to each other and operable therefor from outside the electrode to create a clamping action in the holder to sustain the electrode.
28. In an inside holder for hollow electrodes, the combination of a gripping member comprising a plurality of gripping parts, an actuating member therefor provided with wedge-shape contours whereby the said gripping member parts are brought into operation, and means operable from outside the electrode for effecting an operative engagement of the actuating member with the gripping member.
29. In an inside holder for a hollow electrode comprising cooperating members extending from above the top of the electrode down into the interior thereof and movable in respect to each other to create a clamping action in the holder to sustain the electrode.
30. In an inside holder for hollow electrodes, the combination of a gripping member comprising a plurality of gripping parts, an actuating member therefor provided with wedge-shape contours whereby the gripping member parts are brought into operation, means extending from the gripping member and the actuating member whereby the said members may be positioned in the electrode from the top thereof and whereby an operative engagement between the gripping member and the actuating member may be effected.

Signed at Christiania, Norway, this 15th day of April, 1919.

CARL WILHELM SÖDERBERG.
